UNITED STATES PATENT OFFICE.

HENRY TILDEN, OF MINNEAPOLIS, MINNESOTA.

HEATING-STOVE.

SPECIFICATION forming part of Letters Patent No. 359,696, dated March 22, 1867.

Application filed November 9, 1885. Serial No. 182,217. (No model.)

To all whom it may concern:

Be it known that I, HENRY TILDEN, a citizen of the United States, residing at Minneapolis, in the county of Hennepin and State 5 of Minnesota, have invented certain new and useful Improvements in Heating-Stoves, of which the following is a specification.

My invention relates to stoves for heating purposes; and the object of the invention is 10 the utilization, by simple and inexpensive means, of the larger portion of the heat which in stoves of ordinary construction escapes unutilized through the smoke-flues. This object is accomplished by the construction and arrangement of devices illustrated in the accompanying drawings, in which—

Figure 1 is an elevation of a stove provided with my improvements. Fig. 2 is a central vertical section of the same. Figs. 3 and 4 20 are plan views of the grates used in the front and rear portions, respectively, of the stove for supporting fire-bricks; and Fig. 5 is a slide used for controlling the draft, in connection with the grate shown in Fig. 3.

25 The stove selected for illustration is a wood-burning stove of oval form in cross-section, and the parts hereinafter described are shaped with reference to that form; but it will be obvious that the improvements can be adapted 30 by change of form to use in connection with stoves of other forms than that illustrated in the drawings.

In the drawings, A represents the fire-box, and B the ordinary sheet-iron drum. b is the 35 usual smoke-flue leading to the chimney, and connected with the drum B near its lower end and with the upper portion of the drum B by a branch pipe, b'. The usual dampers, b², are provided in the pipes b and b'.

40 An air-inlet, a, to the combustion-chamber is provided in the front plate, and a door, a', is provided in the side of the combustion-chamber. On the top of the combustion-chamber is fitted a grate, C, adapted to support 45 several tiers of fire-bricks.

d d are bricks of fire-clay or other suitable material piled vertically in open courses alternately laid to form a devious passage for the products of combustion.

50 The bricks may be made to conform somewhat to the shape of the stove, so that they may be more conveniently laid, and they are

preferably so spaced in laying them that the aggregate areas of the spaces on any given plane will about equal the smoke-flue air-space.

It is desirable to divide the drum by a partition, e, fitting to the sides of the drum, and extending from the grate C to about the lower line of the pipe b'. The bricks in the rear of this partition should be supported above the opening to the smoke-flue b, and for this purpose there is provided a grate, f, which may be secured to the sides of the drum and to the partition e.

The portion of the grate C in rear of the partition has draft-openings h, over which is a sliding plate, s, having corresponding openings h' for opening or closing the holes to control the draft. In starting a fire, or whenever a direct and strong draft is desired, the slide may be shifted by means of the handle s', which projects outside the stove, and the openings h' of the slide brought in coincidence with openings h of the grate. At other times, when it is desired to have the draft through the drum B, these holes are kept closed. The passage of the heated products of combustion in a zig-zag course through the series of bricks retards the escape of those products and results in heating the bricks to a high degree, and the heat thus stored is afterward given off by gradual radiation.

In the upper portion of the drum B it is desirable to have openings controlled by slides i, so that when the bricks have become heated and when there may be no smoke or gas rising from the fire-box the slides i may be withdrawn and the dampers b² closed, thereby allowing the heated air to pass out of the openings in the drum.

It is desirable also to form a secondary drum, B', at the top of the stove by interposing a close-fitting plate, g, in the upper portion of the drum B, and this drum B' may be supplied with draft-openings controlled by slides i' to permit a circulation of air through the drum. The plate g becomes very hot and heats the air as it circulates in the drum, and thence it passes out to aid in warming the apartment.

What I claim herein, and desire to secure by Letters Patent, is—

1. The combination, in a heating-stove having a fire-chamber, a drum, and an intermediate grate, of a partition dividing said drum

except the upper portion thereof, into front and rear compartments, an escape-flue communicating with the lower portion of said rear compartment, a damper for controlling the draft from the fire-chamber directly to said escape-flue, a grate in said rear compartment immediately above the inlet to said escape-flue, and open courses of fire-bricks alternately laid to form devious passages in said compartments for the products of combustion, substantially as set forth.

2. In a heater, the combination of the fire-box A, the drum B, the escape-flues b b', provided with dampers b², the grate C, the partition e, dividing said drum into compartments, the draft-regulator s, the grate f, and the fire-bricks d, all constructed and arranged substantially as set forth.

HENRY TILDEN.
